UNITED STATES PATENT OFFICE.

PHILIP W. MARKOWITZ, OF BROOKLYN, NEW YORK.

ENVELOPE.

Application filed August 20, 1920. Serial No. 404,878.

To all whom it may concern:

Be it known that I, PHILIP W. MARKOWITZ, a citizen of the United States, residing at Brooklyn, in the county of Kings and State of New York, have invented certain new and useful Improvements in an Envelope, of which the following is a specification.

This invention relates to combined letter heads and envelopes, and has for one of its objects to simplify and improve the construction and increase the efficiency and utility of the same.

Another object of the invention is to provide a device of this character having means whereby the sheet containing the letter head or other imprinted matter may be supported in a suitable filing device without decreasing the area of the imprinted or written matter, or covering or concealing such matter.

With these and other objects in view, the invention consists in certain novel features of construction as hereinafter shown and described and then specifically pointed out in the claim, and in the drawings illustrative of the preferred embodiment of the invention.

Figure 1 is a view of the improved device before the closure flap is folded over to complete the envelope,

Fig. 2 is a perspective view with the device partly folded,

Fig. 3 is a perspective view from the front or address side with the device fully folded.

Fig. 4 is a perspective view from the rear or closure flap side,

Fig. 5 is a perspective view showing how the envelope may be still further reduced in size.

The improved device comprises a sheet of paper, represented as a whole at 10, and with a portion 11 extending from one edge and constituting a closure flap when the device is folded into envelope form, as shown in Figs. 3 and 4. The main closure flap 11 is formed with smaller extensions 12 at the ends adapted to be folded over the adjacent portions of the body 10 as shown in Fig. 3, when the device is arranged in envelope form.

Formed in the outer edge of the combined closure flap 11 near the ends are recesses or hollow portions 19, and extending between the recesses and spaced from the outer edge of the flap is a line of severing punctures 18 and adhesive material indicated at 14 is ap-

plied to the closure flap externally of the punctures 18 and between the recesses 19.

The extension 11 is provided with apertures to engage over filing pins or needles, as hereinafter explained.

The sheet 10 with its closure flap 11 and end extensions 12 will be furnished in unfolded shape and may be utilized as an ordinary letter head, bill head, to receive statements or other like matter, or used for circulars, or other like matter, as may be required.

Printed matter of any kind may be applied to the body of the sheet and after the written matter has been applied, the sheet 70 is folded over along the line 16 and the two thicknesses thus produced again folded along the lines 17 to produce the structure shown in Fig. 2. The closure flap 11 is then folded over the adjacent portions of the 75 folded sheet and the end flaps 12 folded over and whole closure flap sealed by moistening the adhesive material in the ordinary manner.

The adhesive 14 is stopped short of the recesses 19, so that when the envelope is to be opened, an envelope opener may be inserted through the recesses 19 and the flap severed along the line 18 and likewise along the lines between the body of the flap 11 and the end 85 flaps 12.

This action releases the portion of the flap 11 within the lines of the adhesive material, leaving the portions having the adhesive upon the back or outer face of the envelope 90 when opened and likewise leaving the main portion of the flap free from adhesive material.

Lines of severing punctures 18 are produced near the free edge of the extension or 95 closure flap 11, to enable the envelope to be opened without destroying the closure flap, so that after the sealed envelope is opened, the closure with its apertures 15 may be employed as a means for suspending the sheet 100 from filing pins or pegs of the usual form.

Thus the sheets may be preserved in readily accessible condition, and in position for ready reference.

The main body portion 10 may be utilized 105 as an ordinary letter head, or bill head, to contain circular matter, or the like, and combines in one sheet all the advantages of an ordinary letter head, bill head, statement, note head, or circular together with the en- 110

velope, thus effecting a saving in the paper of either the letter head or the envelope besides the labor of handling one or the other.

The improved device also effects a material saving in time and labor, as it only requires two folds for an ordinary letter or bill head and only one fold for a note head or a smaller bill or statement head.

The body 10 may be of any required size, and with any required number of folds.

The preferred embodiment of the invention is disclosed in the drawings and set forth in the specification, but it will be understood that any modification within the scope of the claim may be made in the construction without departing from the principle of the invention or sacrificing any of its advantages.

I claim:

20 A combined envelope and letter sheet com-

prising a body portion, a combined closure and suspension flap extending from one edge and having extensions at the ends, the extensions and the outer edge of the flap having adhesive material and with severing punctures between the adhesive and the body of the flap, the faces of said flap within the adhesive covered portions being free from matter and the outer edge at the ends having recesses free from the adhesive, whereby the device may be folded and the closure flap sealed thereon and released by inserting an instrument through the recesses and severing the flap along the apertures, leaving the inner face of the flap free to serve as a suspension means.

In testimony whereof, I affix my signature hereto.

PHILIP W. MARKOWITZ.
